(57) **CLAIM**

The ornamental design for a closing mechanism for an insulated container, as shown and described.

DESCRIPTION

FIG. 1 is a front perspective view of the insulated container with the lid in the closed position and the closing mechanism in the fully unlatched position;

FIG. 2 is a front view thereof;

FIG. 3 is a rear view thereof;

FIG. 4 is left side view thereof;

FIG. 5 is a right side view thereof;

FIG. 6 is a top view thereof;

FIG. 7 is a bottom view thereof;

FIG. 8 is a front perspective view of the insulated container with the lid in the open position and the closing mechanism in the fully unlatched position;

FIG. 9 is a front perspective view of the insulated container with the lid in the closed position and the closing mechanism in the extended unlatched position;

FIG. 10 is a front perspective view of the insulated container the lid in the closed position and the closing mechanism in the partially latched position;

FIG. 11 is a front perspective view of the insulated container with the lid in the closed position and the closing mechanism in the fully latched position;

FIG. 12 is a bottom view of the insulated container with the closing mechanism in the extended unlatched position; and, FIG. 13 is a right side view of the insulated container with the closing mechanism in the extended unlatched position. The broken lines depict portions of the closing mechanism for an insulated container that form no part of the claimed design.
